WELL APPARATUS

Filed March 24, 1926

Fig. 1.

UNITED STATES PATENT OFFICE

FRANK C. KELLEY, OF LONG BEACH, CALIFORNIA, ASSIGNOR OF ONE-HALF TO ELMER W. RIGGLE, OF LOS ANGELES, CALIFORNIA

WELL APPARATUS

Application filed March 24, 1926. Serial No. 97,019.

This invention relates to well apparatus of the type which is useful in oil well practice and has for a particular object the provision of novel means for preventing sanding of the various pump parts and so that circulation of oil from the oil-bearing sands through the tubing and casing may be at all times maintained.

At the present time considerable difficulty is experienced in the sanding up of wells, the sand being so heavy as to prevent proper operation of the standing and working valves, with the result that the pumping efficiency of the well is decreased, which of course would decrease the normal flow of oil at the surface of the well.

This invention particularly relates to the type of pump known as the "macaroni" style in which the fluid is pumped through tubular pump or sucker rods and delivered at the surface through a flexible or jointed connection to storage.

An object of the present invention is the provision of means whereby pressure is built up within the tubing in accordance with use and requirements so that a continuous circulation is maintained down through the tubing and up through the hollow pump rods and sanding of the well is practically impossible. The inventor is aware that certain methods are now in use in oil well practice which utilize steam pressure, but such devices are open to the objection that they are not automatic and require the attention of an operator to build up the steam pressure in case the oil does not flow properly.

With the present invention the device will build its own pressure in accordance with requirement, and to that end the device may be considered automatic. For instance, if a pressure of 600 pounds is required to maintain free circulation, it may so happen that after a certain period of use greater pressure is required, say 1400 pounds, and with the present device the pressure would be built up to the required amount so that a free circulation of the oil would be maintained. Obviously, if 1400 pounds were required for a duration of time and then the well owner required 600 pounds, the device would function auto-

matically for this reduced pressure, and without the necessity of the operator being on the ground.

Other objects of the invention will appear as the specification proceeds and the invention 55 contemplates among its objects the provision of well apparatus which is fool-proof in operation, automatic, and which will effectively prevent sanding of a well.

With the above and other objects in view, 60 the invention consists in the novel and useful provision, formation, construction, association and relative arrangement of parts, members and features, all as shown in certain embodiments in the accompanying drawing, described generally, and finally pointed out in the claims.

In the drawing:

Figure 1 is a fragmentary elevation showing a well derrick, tank and casing associated 70 with my invention;

Figure 2 is a fragmentary vertical sectional view showing details of my invention; and,

Figure 3 is a further detail of the invention.

Corresponding parts in all the figures are 75 designated by the same reference characters.

In the drawing, A designates as an entirety, an oil well rig with the usual pumping means and casing within a well hole, and B designates as an entirety the improved means for 80 maintaining a high pressure circulating system in the well casing, tubing and sucker rods, the means B embodying the invention.

The usual well casing 1, of which there are several strings as shown in Figure 1, is provided, and within the well casing is tubing 2, as well as hollow pump or sucker rods 3. The casing is joined with the usual casing head 4 in a well derrick 5, and piping 6 is flexibly connected with the pump or sucker rods 3 as shown at 7, whereby oil pumped to the surface of the well may be conducted to a suitable reservoir 8. The usual plunger pumps may be utilized, and in this connection a walking beam 9 mounted on a Samson post 10 is driven by means 11 to raise and lower the hollow sucker rods through the connecting rod 12. All of this is old and in general use at the present time, and the part of the invention that is new relates to the means B which includes a 100

pump *a* adapted to be actuated by movement of the walking beam 9. This pump *a* is of ordinary construction including a cylinder 13, one end of which is provided with a valve 14 with a valved piston 15 within the cylinder. The end of the cylinder adjacent the valve 14 is screw-threaded as at 16 for reception of a pipe 17 and piping 18 connects with the pipe 17 and enters the reservoir 8 with an open end 10 of said pipe adjacent the top surface of any oil within the said reservoir as shown at 19. In fact, a float 20 is adapted to carry such open end and a pipe length is mounted for movement in accordance with oil level. This open end 15 of the pipe is maintained adjacent the top surface so that oil which is pumped through the piping 6 will allow the sand within the same to settle and fresh oil will be received in the piping 18. The piston 15 is provided with 20 a piston arm 21, which arm is joined with the walking beam 9, as shown at 22. Thus up and down movement of the walking beam will actuate the pump, an upward movement of the walking beam drawing oil through the 25 piping 18 past the valve 14 and downward movement of the walking beam closing the valve in the piston 15 so that upon a reverse movement of the piston oil above the valve piston 15 will be pumped from the cylinder 30 13, through piping 23, which piping communicates with a tubing head 24 above the casing head.

Referring particularly to Figure 2 the tubing head is of the usual construction and 35 acts as an anchorage for the tubing 2, with the hollow sucker rod 3 passed through such tubing head, and the usual packer or gland 25 surrounding the periphery of the hollow sucker rod where it passes through the tubing 40 head. The tubing extends downwardly within the well and is joined to a collar 26 which in turn carries a pump barrel 27. Within the pump casing is a liner 28 spaced from the pump casing slightly and the liner in turn has 45 received within the same a plunger 29. This plunger has connected thereto a plunger valve 30 constituting the working valve and the cage 31 of such plunger valve is slightly spaced from the inner surface of the liner 28. A rod or bar 32 transversely spans the gap in 50 the cage 31 so as to limit upward movement of the ball 33 of such valve. Above the bar 32 is a hollow rod 34 which spans the gap of such cage and likewise has communication 55 exterior the cage, as shown at 35 and 36. Secured to this hollow tube is a small valve 37. This valve is similar to the standing valve shown at 14 in the pump, which is to say, it includes a cage 38 which is secured to a threaded member 39, which member acts as a valve seat and which member likewise is secured to the tube 34. This member 39 is provided with a central bore 40 which communicates with the bore in the tube 34. The hollow sucker rod is secured by screw threading or

otherwise, as shown at 41 to the cage 31. The pump liner is provided with transverse openings 42 so that there is communication between the sucker rod and the interior of the liner and the exterior of the liner and interior of the barrel 27.

Connected to the piping 23 through the medium of a T 43 is a control valve 44 for regulating the pressure of the oil pumped through the piping 23. This control valve comprises the following elements: a valve housing 45 having a valve seat upon which is a ball valve 46, piping 47 communicating with the T, and with such valve, and above the valve is other piping 48 which may lead back to the reservoir 8. At one side of the valve housing or casing is an arm 49, and pivoted to such arm 49 is a lever 50 adapted to carry a slide weight 51. Connected to the arm 50 is a stem 52 which is received within the valve and adapted to have an end thereof bear against the ball 46 to maintain the same on the valve seat. The weight 51 is adjusted so that a certain pressure will lift the ball from its seat and allow the fluid being pumped to be passed through the piping 48.

The operation of the device is as follows: When the walking beam is in operation and fluid is being pumped from the well, fresh oil is constantly being pumped through the piping 18 past the pump *a*, through the piping 23 and down within the tubing 2. This oil in turn is pumped under pressure into the space included between the cage 31 of the working valve and the liner, and likewise through the openings 42 to the space included between the barrel and the liner. This oil is fresh and clean and the oil that is received between the barrel and the liner is allowed to contact with the plunger 29 to lubricate the surface between the plunger and the liner through the medium of openings 53 in the said liner. Likewise fresh oil under pressure is passed inwardly of the hollow rod 34 and raises the ball of the valve 37 so that fresh oil in turn is pumped upwardly through the hollow sucker rod along with the oil being lifted from the oil-bearing sands. It is thus evident that a sanding up of the working valve is practically impossible of accomplishment. If we assume that the oil being lifted is very sandy, and there is a tendency for the sand to settle and close the working valve, pressure will gradually build up in the line as the walking beam operates, so that the fresh oil being forced through the pipe 23 and downwardly within the tubing, will finally reach a pressure sufficient to force the sand that has accumulated upwardly, and thus relieve the sanded condition of the hollow sucker rods and permit the working valve to again function properly. To this end the weight 51 can be adjusted so that any degree of pressure desired may be attained, and it is obvious that such

a device would be automatic, not requiring the attention of the operator, as the weight may be placed at a point where an excess of pressure beyond the setting of the weight 5 might be sufficient to burst a pipe so that if a certain pressure is exceeded, the valve would open to prevent the piping being broken. In any event, a high pressure circulating system for wells is detailed by the construction just described, and one that will 10 function continuously and without attention.

It is obvious that various changes and modifications may be made in practicing the invention, in departure from the particular 15 showing of the drawing, without departing from the true spirit of the invention.

Having thus disclosed my invention, I claim and desire to secure by Letters Patent:

1. Improvements in oil well apparatus, 20 having a tubing within a well hole, a pump within said tubing and working and standing valves associated with the tubing and said pump, including a walking beam adapted to actuate said pump, a second pump associated with the walking beam and a connection between said second pump and the space above said working valve, there being means for supplying fresh oil to said second pump and whereby when the walking beam 25 is operated the said pumps are operated, the first pump to lift oil from the oil-bearing sands and the second pump to force clean oil above the working valve to maintain the working valve operative and prevent a sanding up thereof.

2. Improvements in oil well apparatus, 30 having a tubing within a well hole, a pump within said tubing and working and standing valves associated with the tubing and said pump, and a walking beam adapted to actuate said pump, including a second pump associated with the walking beam and a connection between said second pump and the space above said working valve, there being 35 means for supplying fresh oil to said second pump and whereby when the walking beam is operated the said pumps are operated, the first pump to lift oil from the oil-bearing sands and the second pump to force clean oil above the working valve to maintain the working valve operative and prevent sanding up thereof; there being automatic means 45 for regulating the pressure of oil pumped by the second named pump.

50 In testimony whereof, I have signed my name to this specification.

FRANK C. KELLEY.
